15 Claims. (Cl. 167—65)

This invention relates to quaternary ammonium salts and pharmaceutical preparations containing them.

It has been found that there is a class of quaternary ammonium salts of 1:2:3:4 - tetrahydroisoquinoline whose members modify the actions of the sympathomimetic amines, for example adrenaline, in animals, and which class of salts is therefore, of pharmaceutical and veterinary importance.

Accordingly, one aspect of the present invention provides a pharmaceutical or veterinary composition which essentially contains a pharmacologically active quaternary ammonium salt of 1:2:3:4-tetrahydroisoquinoline having the structural formula:

(I)

wherein R₁ and R₂, which may be the same or different, represent methyl, ethyl, n-propyl, iso-propyl, alkyl, propargyl or 2-hydroxyethyl groups and X⁻ represents a non-toxic anion, for example a chloride, bromide or iodide radical, or an alkyl sulphonate or a substituted or unsubstituted aryl sulphonate group.

Most of such quaternary ammonium salts are believed to be novel compounds and such of the salts as have been mentioned in the literature have not had any pharmacological activity attributed to them. The novel salts provided by the present invention are quaternary ammonium salts of 1:2:3:4-tetrahydroisoquinoline as defined above except when one of the groups R₁ or R₂ contains one carbon atom and the other group contains from one to three carbon atoms or is hydroxyethyl and X⁻ is an iodine anion.

As has already been mentioned, the quaternary ammonium salts as defined above have been found to modify the actions of sympathomimetic amines.

The following compounds are of particular interest in that they have been shown to be effective in causing in animals a selective block of the peripheral sympathetic (adrenergic) nervous system without affecting the peripheral parasympathetic nervous system and without causing ganglion block:

2-methyl-2-ethyl-1:2:3:4-tetrahydroisoquinoline, for example the iodide, bromide and, preferably, the p-toluenesulphonate;

2-methyl-2-allyl-1:2:3:4-tetrahydroisoquinoline, for example the bromide;

2:2-diethyl-1:2:3:4-tetrahydroisoquinoline, for example the iodide; and

2-ethyl-2-(2-hydroxyethyl)-1:2:3:4 - tetrahydroisoquinoline, for example the bromide.

Others of the compounds defined above also modify the actions of the sympathomimetic amines. Examples of such compounds which exert a hypotensive effect are quaternary ammonium salts of:

2:2-dimethyl-1:2:3:4-tetrahydroisoquinoline, for example the iodide; and

2

2-methyl-2-n-propyl-1:2:3:4 - tetrahydroisoquinoline, for example the iodide.

Other examples of such compounds may exert a mildly hypertensive effect.

The pharmacologically active quaternary ammonium salts of 1:2:3:4-tetrahydroisoquinoline as defined above may be provided as a pharmaceutical or veterinary composition in a suitable form for dosage, which composition contains essentially at least one pharmacologically active salt and which also comprises a pharmaceutical carrier base which may be a liquid, semi-solid or solid. Thus for example, the composition may be in a form suitable for parenteral administration which may be sterile solutions, suspensions in water or other liquids, with or without the addition of soluble or insoluble diluents and/or solid or liquid excipients.

In clinical practice the compounds of the present invention will normally be administered orally and in consequence, the preferred formulations are of the kind which are most suitable for oral ingestion.

Preparations for oral administration can be liquids or solids or any combination of these forms such as solutions, suspensions, emulsions, elixirs, syrups, powders or tablets.

Pharmaceutical preparations for administration of the active therapeutic agents in unit dose form can take the form of compressed powders or of a powder enclosed in a suitable capsule of absorbable material such as gelatin. These compressed powders or tablets can take the form of the active material admixed with suitable excipients and/or diluents such as starch, lactose, stearic acid, magnesium stearate, dextrin or the like.

The pharmacologically active salt may be presented in the form of a resinate to give a relatively slow and even release of the drug when acted upon by the normal contents of the gastro-intestinal tract, as described in for example United Kingdom patent specifications No. 857,193 and 857,194.

According to another aspect of the invention, there is provided a method of preparing the quaternary ammonium salts having the formula defined above, which method comprises heating a N-substituted-1:2:3:4-tetrahydroisoquinoline having the formula:

wherein R₁ and R₂ have the meanings defined above, with an alkylating agent of the formula R₂X or R₁X respectively, preferably in the presence of an appropriate organic solvent, such as for example acetone or methyl ethyl ketone. The product either separates and can be filtered off, or is precipitated for example by the addition of ether.

The N-allyl-1:2:3:4-tetrahydroisoquinoline starting material may be prepared from 1:2:3:4-tetrahydroisoquinoline by reaction with an allyl halide in the presence of a base, such as for example potassium carbonate, either alone or in a suitable solvent, such as for example acetone. The tertiary amine product is often contaminated with the unsubstituted tetrahydroisoquinoline and in this case may be separated either by fractional distillation or by the Hinsberg technique. The tertiary amine starting material prepared in this manner may then be quaternized in the above-described manner.

The N-propargyl-1:2:3:4-tetrahydroisoquinoline starting material, which is a new compound, may itself be prepared from 1:2:3:4-tetrahydroisoquinoline by reaction

with 2:3-dibromoprop-1-ene, followed by dehydrohalogenation with a suitable base of the N-(2-bromoprop-2-ene)-1:2:3:4-tetrahydroisoquinoline so formed. The resulting tertiary base may then be quaternized in the manner already described.

The invention is illustrated by the following examples of the preparation of the quaternary ammonium salts, the products in each case being white crystalline solids, with a tendency to hygroscopicity.

Infra red spectra of these compounds show bands at 1429, 1010, 1099 and 763 cm.⁻¹ which are expected from quaternary tetrahydroisoquinolines.

Example 1

2-methyl-1:2:3:4-tetrahydroisoquinoline (6.5 g.), ethyl bromide (10 g.) and acetone (10 ml.) were heated on the steam bath under reflux for three hours. After cooling, the resulting precipitate was collected, washed with acetone and recrystallized by dissolving in the minimum amount of dry alcohol, adding acetone (8 ml.) and then ether until crystallization was complete to give 2-ethyl-2-methyl-1:2:3:4-tetrahydroisoquinolinium bromide, M.P. 153-155° C. Analysis.—C, 56.2%; H, 7.1%; N, 5.3%. $C_{12}H_{18}NBr$ requires C, 56.25%; H, 7.1%; N, 5.5%.

Example 2

A mixture of 2-methyl-1:2:3:4-tetrahydroisoquinoline (25 g.) ethyl-p-toluenesulphonate (37.2 g.) and methyl ethyl ketone (75 ml.) was heated on a steam bath for 2½ hours. On prolonged standing at room temperature the solution deposited crystals. These were filtered off, washed with methyl ethyl ketone, to give 2-ethyl-2-methyl-1:2:3:4-tetrahydroisoquinolinium p-toluene sulphonate, M.P. 102-106° C. Analysis.—C, 65.67%; H, 7.26%; N, 4.10%. $C_{12}H_{18}N.C_7H_7SO_3$ requires C, 65.67%; H, 7.25%; N, 4.03%.

Example 3

Allyl bromide (12.1 g.) was added slowly to a solution of 2-methyl-1:2:3:4-tetrahydroisoquinoline (14.7 g.) in methyl ethyl ketone (50 ml.) and the mixture heated on a steam bath for 1 hour. The syrup which separated was crystallized by trituration and was recrystallized from isopropanol-ether to give 2-allyl-2-methyl-1:2:3:4-tetrahydroisoquinolinium bromide M.P. 158-160° C. Analysis.—C, 58.4%; H, 6.79%; N, 5.26%; Br, 29.72%. $C_{13}H_{18}NBr$ requires C, 58.22%; H, 6.76%; N, 5.22%; Br, 29.80%.

Example 4

Propargyl bromide (11.9 g.) was slowly added to a solution of 2-methyl-1:2:3:4-tetrahydroisoquinoline (14.7 g.) in methyl ethyl ketone (100 ml.). A syrup settled out immediately and crystallized on cooling. The resulting product was filtered off and recrystallized from ethanol to give 2-methyl-2-propargyl-1:2:3:4-tetrahydroisoquinolinium bromide, M.P. 195-197° C. Analysis.—C, 58.82%; H, 6.18%; N, 5.58%. $C_{13}H_{16}NBr$ requires C, 58.65%; H, 6.06%; N, 5.26%.

Example 5

Ethyl iodide (8 g.) was slowly added to a solution of 2-ethyl-1:2:3:4-tetrahydroisoquinoline (8 g.) in methyl ethyl ketone (40 ml.) and the mixture heated on a steam bath for 1 hour. The crystalline product was filtered off and recrystallized from isopropanol to give 2:2-diethyl-1:2:3:4-tetrahydroisoquinolinium iodide, M.P. 158-160° C. Analysis.—C, 49.28%; H, 6.41%; N, 4.05%. $C_{13}H_{20}NI$ requires C, 49.21%; H, 6.35%; N, 4.42%.

Example 6

A mixture of 2-ethyl-1:2:3:4-tetrahydroisoquinoline (10 g.), n-propyl iodide (11 g.) and methyl ethyl ketone (40 ml.) was heated on a steam bath for 3 hours, cooled and ether added. The precipitated syrup crystallized on trituration with ether. Recrystallization from isopropanol

gave 2-ethyl-2-n-propyl-1:2:3:4-tetrahydroisoquinolinium iodide, M.P. 108-111° C. Analysis.—C, 50.83%; H, 6.63%; N, 4.45%; I, 37.87%. $C_{14}H_{22}NI$ requires C, 50.76%; H, 6.695%; N, 4.23%; I, 38.31%.

5

Example 7

Allyl bromide (8 g.) was added slowly to a solution of 2-ethyl-1:2:3:4-tetrahydroisoquinoline (10 g.) in methyl ethyl ketone (40 ml.) and the mixture heated on the steam bath for 1 hour. The syrup which separated was crystallized by trituration with ether. Recrystallization from ethanol-ether gave 2-allyl-2-ethyl-1:2:3:4-tetrahydroisoquinolinium bromide, M.P. 95-100° C.

Example 8

Allyl bromide (36.6 g.) was added slowly to 1:2:3:4-tetrahydroisoquinoline (39.9 g.) with cooling. Potassium carbonate (41.4 g.) was then added and the mixture heated on a steam bath for 4 hours. Water (100 ml.) was added to the cooled mixture followed by 10 N sodium hydroxide (20 ml.). The oil which separated was isolated by ether extraction. The oil distilled at 114-122° C/12 mm., and from the infra-red spectra thereof was shown to be a mixture of 2-allyl-1:2:3:4-tetrahydroisoquinoline and 1:2:3:4-tetrahydroisoquinoline. The oil was submitted to a Hinsberg separation using sodium hydroxide and benzene sulphonyl chloride. The 2-allyl-1:2:3:4-tetrahydroisoquinoline did not form a benzene sulphonamide and remained soluble in dilute hydrochloric acid. Basification of the acidic solution with 10 N sodium hydroxide liberated the 2-allyl-1:2:3:4-tetrahydroisoquinoline which distilled at 118-122° C/12 mm.

Allyl bromide (8 g.) was slowly added to a solution in methyl ethyl ketone (40 ml.) of 2-allyl-1:2:3:4-tetrahydroisoquinoline (9 g.) prepared in the above manner, and the resulting mixture was heated on a steam bath for 2 hours. The precipitated syrup slowly crystallized on trituration with ether. Recrystallization from isopropanol ether gave 2:2-diethyl-1:2:3:4-tetrahydroisoquinolinium bromide, M.P. 115-118° C. Analysis.—C, 60.77%; H, 6.69%; N, 4.59%; Br, 27.7%. $C_{15}H_{20}NBr$ requires C, 61.24%; H, 6.85%; N, 4.76%; Br, 27.16%.

Example 9

A mixture of 2-ethyl-1:2:3:4-tetrahydroisoquinoline (10 g.), ethylene bromohydrin (10 g.) and methyl ethyl ketone (40 ml.) was heated on a steam bath for 3 hours, cooled, and ether added. The resulting precipitated syrup crystallized on trituration with ether. Recrystallization from ethanol-ether gave 2-ethyl-2-(2'-hydroxyethyl)-1:2:3:4-tetrahydroisoquinolinium bromide, M.P. 65-70° C.

Example 10

1:2:3:4-tetrahydroisoquinoline (26.5 g.) was added slowly whilst cooling to 80% formic acid (13 g.). 38% formalin solution (20 g.) was then run in and the resulting mixture was heated on a steam bath. When the evolution of CO_2 had almost ceased, 3 mls. formic acid and 3 mls. formalin were added and heating was continued for a further 2 hours.

The mixture was then cooled and water (50 mls.) was added, whereafter, the solution was rendered strongly basic by the addition of KOH solution. The oil which separated was extracted with ether three times and the combined ether extracts were washed twice with water, dried and distilled. The N-methylated compound distilling at 108-112° C/16 mm. was collected in a yield of 17.0 g.

Ethyl iodide (10 mls.) was added to a solution in acetone (40 mls.) of 2-methyl-1:2:3:5-tetrahydroisoquinoline prepared as described above and the resulting mixture was then heated on a steam bath until reaction was complete. Ether was then added to the mixture and the solid which then formed was collected in a yield of 17.0 g., M.P. 139-142° C.

Recrystallization from alcohol-ether with charcoaling gave 2 - methyl-2-ethyl-1:2:3:4-tetrahydroisoquinolinium iodide, MP. 140-141° C. *Analysis*.—C, 47.9%; H, 6.0%; N, 4.7%. $C_{12}N_3NI$ requires C, 47.5%; H, 6.0%; N, 4.6%.

Example 11

Methyl iodide (15 g.) was added slowly to a solution of 2-methyl-1:2:3:4-tetrahydroisoquinoline (14.7 g.) in methyl ethyl ketone (50 ml. and the mixture heated on a steam bath for 1 hour. The crystalline product which formed was filtered off and recrystallized from ethanol to give 2:2 - dimethyl-1:2:3:4-tetrahydroisoquinolinium iodide (15.0 g.) having M.P. 194-196° C.

By way of further exemplification, other compounds which have been made in accordance with the invention include:

- 2 - methyl - 2 - (2'-hydroxyethyl)-1:2:3:4-tetrahydroisoquinolinium bromide, M.P. 131-133° C. and iodide, M.P. 151-153° C.
 2 - methyl - 2-n-propyl-1:2:3:4-tetrahydroisoquinolinium iodide, M.P. 122-124° C. and
 2 - methyl - 2-iso-propyl-1:2:3:4-tetrahydroisoquinolinium iodide, M.P. 191-191.5° C.

Example 12

2:3-dibromoprop-1-ene (30 g.) was slowly added to an ice cold solution of 1:2:3:4-tetrahydroisoquinoline (39.9 g.) in ether (160 ml.) and the mixture allowed to stand overnight at room temperature. The crystals of 1:2:3:4-tetrahydroisoquinoline hydrobromide were filtered off and the ethereal solution distilled. N-(2-bromoprop-2-ene)-1:2:3:4-tetrahydroisoquinoline was collected at 96-100° C./0.15 mm.

N-(2-bromoprop-2-ene)-1:2:3:4-tetrahydroisoquinoline (31.8 g.) was slowly added (over 3/4 hour) to a solution of potassium hydroxide (14 g.) in ethylene glycol (100 ml.), the temperature of the well agitated mixture being kept at 130-140° C. The solution was allowed to cool to room temperature and then it was poured into water (300 ml.). The basic oil was separated by ether extraction, the ether solution being dried and distilled to give N-propargyl-1:2:3:4-tetrahydroisoquinoline, B.P. 132-8° C./15 mm. Treatment of the base with ether and ethereal hydrogen chloride gave N-propargyl-1:2:3:4-tetrahydroisoquinoline hydrochloride, M.P. 199° C. after recrystallization from ethanol. The propargyl tertiary base and its acid addition salts are new compounds and may, if desired, be incorporated into pharmaceutical preparations for administration purposes, just as described for the quaternary compounds.

To convert the tertiary base into a quaternary compound in accordance with the invention, methyl bromide (4.75 g.) was slowly added to an ice cold solution of N-propargyl-1:2:3:4-tetrahydroisoquinoline (8.55 g.) in methyl ethyl ketone (60 ml.). A syrup separated out which slowly crystallized. This was filtered off and recrystallized from ethanol to give 2-methyl-2-propargyl-1:2:3:4-tetrahydroisoquinolinium bromide, M.P. 195-7° C.

Example 13

Tablets were prepared by granulating and compressing the following ingredients in accordance with known pharmaceutical techniques. Each table contained:

	Mg.
2 - ethyl - 2-methyl-1:2:3:4-tetrahydroisoquinolinium para-toluene sulphonate	200
Calcium phosphate	280
Lactose	200
Ethyl cellulose	9
Maize starch (dried)	21
Magnesium stearate	10
	720

Other 2:2-disubstituted-1:2:3:4-tetrahydroisoquinoline

derivatives may be used in preparing the pharmaceutical compositions instead of the 2-ethyl-2-methyl-paratoluene sulphonate derivative providing that they are within the definition of the general Formula I and that the compounds and compositions containing them modify the action of sympathomimetic amines.

We claim:

1. A method of selectively blocking the peripheral sympathetic nervous system of animals without affecting the peripheral parasympathetic nervous system, which comprises administering to the animal a nontoxic salt selected from the group consisting of salts with a nontoxic anion of 2-methyl-2-ethyl-1:2:3:4-tetrahydroisoquinoline; 2 - methyl-2-allyl-1:2:3:4-tetrahydroisoquinoline; 2,2-diethyl-1:2:3:4-tetrahydroisoquinoline and 2-ethyl-2-(2'-hydroxyethyl)-1:2:3:4-tetrahydroisoquinoline.
2. A method of selectively blocking the peripheral sympathetic nervous system of animals without affecting the peripheral parasympathetic nervous system, which comprises administering to the animal a salt with a non-toxic anion of 2-methyl-2-ethyl-1:2:3:4-tetrahydroisoquinoline.
3. A method of selectively blocking the peripheral sympathetic nervous system of animals without affecting the peripheral parasympathetic nervous system, which comprises administering to the animal a salt with a nontoxic anion of 2-methyl-2-allyl-1:2,3:4-tetrahydroisoquinoline.
4. A method of selectively blocking the peripheral sympathetic nervous system of animals without affecting the peripheral parasympathetic nervous system, which comprises administering to the animal a salt with a nontoxic anion of 2-2-diethyl-1:2:3:4-tetrahydroisoquinoline.
5. A method of selectively blocking the peripheral sympathetic nervous system of animals without affecting the peripheral parasympathetic nervous system, which comprises administering to the animal a salt with a nontoxic anion of 2-ethyl-2-(2'-hydroxyethyl)-1:2:3:4-tetrahydroisoquinoline.
6. The method of reducing the blood pressure of animals without causing ganglion block which comprises administering to the animal a nontoxic salt selected from the group consisting of salts with a nontoxic anion of 2-methyl-2-ethyl-1:2:3:4-tetrahydroisoquinoline; 2-methyl - 2 - allyl - 1:2:3:4 - tetrahydroisoquinoline; 2 - 2 - diethyl-1:2:3:4-tetrahydroisoquinoline; and 2-ethyl-2-(2'-hydroxyethyl)-1:2:3:4-tetrahydroisoquinoline.
7. The method of reducing the blood pressure of animals without causing ganglion block which comprises administering to the animal a salt with a nontoxic anion of 2-methyl-2-ethyl-1:2:3:4-tetrahydroisoquinoline.
8. The method of reducing the blood pressure of animals without causing ganglion block which comprises administering to the animal a salt with a nontoxic anion of 2-methyl-2-allyl-1:2:3:4-tetrahydroisoquinoline.
9. The method of reducing the blood pressure of animals without causing ganglion block which comprises administering to the animal a salt with a nontoxic anion of 2-2-diethyl-1:2:3:4-tetrahydroisoquinoline.
10. The method of reducing the blood pressure of animals without causing ganglion block which comprises administering to the animal a salt with a nontoxic anion of 2 - ethyl - 2 - (2' - hydroxyethyl) - 1:2:3:4 - tetrahydroisoquinoline.
11. A composition useful for the treatment of hypertension in animals, consisting essentially of a nontoxic salt selected from the group consisting of salts with a nontoxic anion of 2-methyl-2-ethyl-1:2:3:4-tetrahydroisoquinoline; 2 - methyl - 2 - allyl - 1:2:3:4 - tetrahydroisoquinoline; 2-2-diethyl-1:2:3:4-tetrahydroisoquinoline; and 2 - ethyl - 2 - (2' - hydroxyethyl) - 1:2:3:4 - tetrahydroisoquinoline; and a therapeutically acceptable carrier.
12. A composition useful for the treatment of hypertension in animals, consisting essentially of a salt with a nontoxic anion of 2-methyl-2-ethyl-1:2:3:4-tetrahydroisoquinoline; and a therapeutically acceptable carrier.

13. A composition useful for the treatment of hypertension in animals, consisting essentially of a salt with a nontoxic anion of 2-methyl-2-allyl-1:2:3:4-tetrahydroisoquinoline; and a therapeutically acceptable carrier.

14. A composition useful for the treatment of hypertension in animals, consisting essentially of a salt with a nontoxic anion of 2-2-diethyl-1:2:3:4-tetrahydroisoquinoline; and a therapeutically acceptable carrier.

15. A composition useful for the treatment of hypertension in animals, consisting essentially of a salt with a nontoxic anion of 2-ethyl-2-(2'-hydroxyethyl)-1:2:3:4-tetrahydroisoquinoline; and a therapeutically acceptable carrier.
